STRIP FORMING MEANS

Lowell R. Newton, Chicago, Ill., assignor to Industrial Patents Corporation, Chicago, Ill., a corporation of Delaware

Application March 2, 1942, Serial No. 432,925

8 Claims. (Cl. 153—2)

This invention relates to a die forming machine and more particularly to a machine for processing straight metal strips to form them into circular bands.

It is an object of this invention to bend a straight metal strip into a circular shape and then press it to have a flared portion around one rim. The ring thus formed may be further shaped so it may be applied to a paper disc as shown in the Walter Patent No. 1,959,971.

The invention here shown performs a partial shaping of the metal strip to be attached to the paper disc and may form one of the operating steps accomplished in a machine like that disclosed in the Swangren Patent No. 2,148,247. This invention is an improvement on the apparatus for performing the initial operation in this patented machine wherein the straight strip is formed into a circular band and is thereafter subjected to a shaping operation during which the upper surface of the ring is flared outwardly.

Referring to the drawings.

Figure 1 is a diagrammatic view of the essential elements of the machine.

Figure 2 is a perspective view partly broken away of the plunger, collar and feed mechanism.

Figure 3 is an elevation partly broken away showing a strip about to be fed into position between the collar and plunger, with the presser poised above this assembly.

Figure 4 is an elevation of the machine showing the plunger and the ring of the material elevated into the turret with the pressing member about to engage the strip to form the outwardly curved flange.

Figure 5 is an elevation of the machine, partly in section, showing the partially formed strip resting in the turret with the plunger and pressing means being retracted.

Figure 6 is a side elevation of the strip which is fed to the machine.

Figure 7 is a perspective of the ring produced in this apparatus.

The Walter patent above mentioned teaches how a strip of metal may be applied to a disc of paper so that the disc may be attached to a body to produce a container. In accordance with his teaching, a strip of metal 10, provided with a serrated edge forming teeth 11 as shown in Figure 6, may be formed into a ring with the teeth projecting downwardly so that they may be pressed through the disc of paper. The teeth pass through the disc and are crimped tight against the paper to provide a metal ring around the edge of the disc with an upwardly flared

flange that may be crimped over the edge of a paper body so that the paper disc may be firmly held in position on the package.

The strip 10 is preferably put through a plurality of forming operations to work it into the proper shape, and as shown in the Swangren patent this may be done in one machine. After the strip is initially formed into a ring with its upper edge outwardly flared, the ring is conveyed to the various working stations by a turret which has an intermittent motion timed to cooperate with the plunger and pressing devices which form the die means.

The present invention is an improvement on the machine shown in the Swangren patent and provides a new means for performing the initial ring forming and flaring operation.

In this present invention, the strip is formed into a ring by driving it into a confined channel until the ends of strip overlap slightly. After the ring is formed, a plunger mechanism is driven upwardly into a turret to place the ring in a working opening provided in the turret. When the ring is so positioned, a pressing member is reciprocated downwardly from above and the upper edge of the ring is flared outwardly over the sides of the opening in the turret. The plunger and pressing elements may then be retracted and the ring will remain in the turret because the flared portion cannot pass through it. The turret is then driven one step around the machine to convey the ring to the next operating position while another strip is being simultaneously driven into the ring forming channel.

Referring to Figure 3, a plunger 14 is mounted for vertical reciprocation and the plunger has a groove 15 cut into its free upper end to provide a shoulder 16. A collar 17 is slidably mounted over the plunger 14 and is guided in its reciprocation along the plunger by pins 18 fixed to the flange 19 integral with the collar 17. The pins 18 reciprocate through suitable apertures 20 formed in flange 21 integral with the plunger and the pin 18 is provided with a head 22 which limits the movement of the collar such that the free end 23 of the collar may be moved to extend somewhat beyond the free end or upper end of the plunger. Springs 24 disposed around pins 18 are confined between flanges 19 and 21 to normally urge the collar upwardly along the plunger.

An open topped channel 25 is provided between the collar 17 and plunger 15 by reason of the groove 16 being cut into the plunger and the collar 17 is provided with an opening 26 which is directed tangentially into the channel 25. The

disposition of opening 26 to direct the strip tangentially into the channel is best seen in Figure 2.

Means to feed a strip of metal 10 into the channel are provided and a fixed guide 30 has a passage 31 provided therein through which the strip may be delivered into the channel 25. A feed tooth 32 mounted on the driven feed bar 33 is adapted to engage the rear end of a strip 10 to drive it into the channel. Bearing guide 34 upon which the feed bar reciprocates also cooperates with the guide 30 to make one of the side walls for passage 31 to confine the strip so that it cannot buckle out of shape as the feed device forces the strip into the channel and the strip is confined on top by flange 35 integral with guide 30. The feed tooth 32 is pivotally mounted on the feed bar 33 and is resiliently urged against a stop pin 36 by spring 37 so that on its return stroke, the tooth may by-pass the strip of metal fed into passage 31 to be subsequently forced into the channel 25.

The strip being driven into the channel 25 is curled around until its ends slightly overlap and when the ring has been completed and the feed bar has started to retract, the plunger is lifted to raise the ring into the opening 40 in turret 41. The opening 40 must of course be aligned with the plunger so that the circular strip will fit neatly into the opening and the plunger continues to drive upwardly as the free end 23 of the collar 17 engages the under surface of the turret opening until the plunger attains the position shown in Figure 4. In this position, the upper edge of the strip extends above the surface of the turret and the lower portion of the strip is engaged between the walls of groove 15 formed in the plunger and the opening 40 of the turret, while the teeth 11 bear upon the shoulder 16. It will be noted that the groove 15 is not as deep as the strip 10 is wide so that the upper edge of the ring stands well above the top end of the plunger.

When the ring has been driven to position in the turret, a presser 45 may then be driven downwardly into the ring to flare the strip outwardly and as shown in Figure 4 the presser has a curved die surface 46 for engaging inside of the ring to bend it outwardly. After the presser has been driven down into the ring to produce the initial flare given the ring, Figure 5, the plunger and presser may both be retracted and the partially formed ring remains in the turret opening 40. The flared upper edge of the ring would prevent it from following the plunger on its return stroke and the opening 40 engages the outer wall of the ring sufficiently to prevent the ring from binding to the presser and following it upwardly as it is retracted.

As soon as the plunger and presser have been retracted sufficiently to withdraw them from the plane of the turret, the turret may be given a forward feeding movement to carry the partially formed ring to the next operating position. The plunger continues its downward movement to the bottom of its stroke in which position the shoulder 16 is aligned with the bottom of the feed passage 31 whereupon a new strip may be forced into the channel 25. It will be noted that as the plunger is retracted the collar is urged upwardly by the springs 24 until its free end extends beyond the free end of the plunger so that the forming channel 25 is again established.

A diagrammatic showing of a drive mechanism to accomplish the desired movements is shown in Figure 1 wherein the drive wheel 50 is connected

by link 51 to the feed bar 33. The feed bar is driven forwardly during one-half of the revolution of wheel 50 and is given a feed stroke to just force a strip of metal completely into the channel with the ends just overlapping.

The plunger assembly may be driven from cam wheel 52 through a cam follower 53 secured to the reciprocating connecting link 54. The link 54 and plunger 15 are driven upwardly while the wheel 50 is retracting the feed bar 33 and the plunger is raised and lowered during one-half a revolution of the cam wheel 52. The plunger must be held stationary during the other half of the revolution of cam wheel 52 while the feed bar 33 drives the strip 10 into the channel.

The presser 45 is driven from cam wheel 55 by cam follower 56 and the reciprocating connecting link 57 and the presser are timed to cooperate properly with the plunger. To accomplish this, the cam wheel 55 is shaped to drive presser 45 into the metal ring just after it is positioned within the opening 40 of the turret. The presser, immediately after engaging the ring to flare the upper edge, is retracted.

The drive means 50, 52 and 55 may be driven by any suitably powered means and with the drive arrangement shown in Figure 1, the wheels 50, 52 and 55 must be driven at the same R. P. M. Wheel 50 must give feed bar 33 a drive stroke of a length to force the strip into the channel, cam 52 must lift the plunger 15 from its position in front of the strip feed up to place the curled strip in the turret opening 40, and cam 55 must drive the presser 45 into the ring held in the turret by the plunger to flare the strip. The sequence of operation of the various parts has been fully set forth above and wheels 50, 52 and 55 are timed with respect to each other to get the desired mode of operation.

The strip having been curled into a ring and flared as above described, may now be carried by the turret to the next operating station where a further die forming step may be performed.

The operation and construction of this invention will be readily understood from the description given above. This is one disclosure of the invention and one manner of performing it, other modifications may occur to those skilled in the art, all of which are contemplated to be within the scope of the following claims.

I claim:

1. A machine for shaping a metal strip comprising cooperating die means including a plunger having a collar mounted therearound, said collar and plunger being movable one relative to the other, one of said plunger and collar elements having a groove cut in the free end thereof, said groove being of a width substantially equal to the width of the strip being shaped, resilient means to urge the other of said plunger and collar elements toward the free end to cover said groove to provide a channel, said collar having an opening therein through which a strip may be fed into the channel, means to feed a strip into the channel whereby it is forced to take the shape of the channel, a pressing member forming another element of the die means, said presser being reciprocable relatively toward said grooved element for engaging the shaped strip in the channel, means for driving said grooved element and said pressing member together, and means positioned between the grooved element and the presser member to receive the strip in said channel and cooperating with said grooved element to hold the strip while said presser member is driven into

engagement with the strip to further shape it.

2. A machine for shaping a metal strip comprising cooperating die means including a plunger having a collar mounted therearound, said collar and plunger being movable one relative to the other, one of said plunger and collar elements having a groove cut in the free end thereof, said groove being of a width substantially equal to the width of the strip being shaped, resilient means to urge the other of said plunger and collar elements toward the free end to cover said groove to provide a channel, said collar having an opening therein through which a strip may be fed into the channel, said opening being disposed to direct the strip tangentially into said channel, means to feed a strip into the channel whereby it is forced to take the shape of the channel, a pressing member reciprocable relatively toward said grooved element for engaging the strip in the channel, means for driving said grooved element and said pressing member together, and means positioned between the grooved element and the presser to receive the strip in said channel and cooperating with said grooved element to hold the strip while said presser member is driven into engagement with the strip to further shape it.

3. A machine for shaping a metal strip comprising cooperating die means including a plunger having a groove formed in one end thereof, said groove being of a width substantially equal to the width of the strip being shaped, a collar mounted around said plunger, resilient means to urge said collar toward the grooved end of said plunger, the free end of said collar extending at least to the end of said plunger whereby a channel is formed between the plunger and collar by reason of said groove, said collar having an opening therein through which a strip may be fed into the channel, means to feed a strip into the channel so that it is forced to take the shape of the channel, a pressing member reciprocable relatively toward said grooved plunger for engaging the strip in the channel, means for driving said plunger and said pressing means together, and means positioned between the plunger and presser to receive a strip in said channel and cooperating with said plunger to hold the strip while said presser member is driven into engagement with the strip to further shape it.

4. A machine for shaping a metal strip comprising cooperating die means including a plunger having a groove formed in one end thereof, said groove being of a width substantially equal to the width of the strip being shaped, a collar mounted around said plunger, resilient means to urge said collar toward the grooved end of said plunger, the free end of said collar extending at least to the end of said plunger whereby a channel is formed between the plunger and collar by reason of said groove, said collar having an opening therein through which a strip may be fed into the channel, means to feed a strip into the channel so that it is forced to take the shape of the channel, a pressing member reciprocable relatively toward said grooved plunger for engaging the strip in the channel, means for driving said plunger and said pressing means together, a plate means positioned between the grooved plunger and the presser, said plate means having an aperture therein to receive the strip in said channel and the said plate means cooperating with said grooved plunger to hold the strip while said presser member is driven into engagement with the strip to further shape it, said collar

being driven away from the grooved end of the plunger as said plate means and plunger means move together to position the strip in said aperture.

5. A machine for shaping a metal strip comprising cooperating die means including a plunger and a groove cut around the free end thereof, said groove being of a width substantially equal to the width of the strip being shaped, a flange integral with said plunger and spaced from said grooved end, a collar slidably mounted over the free end of said plunger, a flange integral with said collar, a plurality of pins fixed to one of said flanges and passing through apertures provided in the other of said flanges to guide the movement of the collar as it slides on the plunger, means on said pins to limit the movement of the collar, said collar extending at least to the free end of said plunger when it is urged to the furthest limit of its possible movement, spring means between said flanges to urge the collar toward the grooved end of the plunger whereby a channel is formed by said groove between the plunger and the collar, said collar having an opening therein through which a strip may be fed into the channel, means to feed a strip into the channel whereby it is forced to take the shape of the channel, a pressing member reciprocable relatively toward said grooved plunger for engaging the strip in the channel, means for driving said plunger and said pressing member together, and turret means positioned between a grooved element and the presser to receive the strip in said channel and cooperating with said grooved plunger to hold the strip while said presser member is driven into engagement with the strip to further shape it.

6. A machine for shaping a metal strip comprising cooperating die means including a plunger having a collar mounted therearound, said collar and plunger being movable one relative to the other, said groove being of a width substantially equal to the width of the strip being shaped, one of said plunger and collar elements having a groove cut in the free end thereof, resilient means to urge the other of said plunger and collar elements toward the free end to cover said groove to provide a channel, said collar having an opening therein through which a strip may be fed into the channel, said opening being disposed to direct the strip tangentially into said channel, means to feed a strip into the channel whereby it is forced to take the shape of the channel, a pressing member reciprocable relatively toward said grooved element for engaging the strip in the channel, stripping means interposed between said plunger and said pressing member for relatively lifting the pressed ring from said plunger as the plunger is retracted, said stripping means driving said resiliently mounted means before it when the plunger and presser member are reciprocated toward each other, and means for reciprocating said plunger and pressing means toward and away from each other.

7. A machine for shaping a metal strip comprising cooperating die means including a plunger having a groove formed in one end thereof, said groove being of a width substantially equal to the width of the strip being shaped, a collar mounted around said plunger, resilient means to urge said collar toward the grooved end of said plunger, the free end of said collar extending at least to the end of said plunger whereby a channel is formed between the plunger and collar by reason of said groove, said collar having

an opening therein through which a strip may be fed into the channel, means to feed a strip into the channel so that it is forced to take the shape of the channel, a pressing member reciprocable relatively toward said grooved plunger for engaging the strip in the channel, stripping means interposed between said plunger and said pressing member for relatively lifting the pressed ring from said plunger as the plunger is retracted, said stripping means driving said resiliently mounted means before it when the plunger and presser member are reciprocated toward each other, and means for reciprocating said plunger and pressing means toward and away from each other.

8. A machine for shaping a metal strip comprising cooperating die means including a plunger and a groove cut around the free end thereof, said groove being of a width substantially equal to the width of the strip being shaped, a flange integral with said plunger and spaced from said grooved end, a collar slidably mounted over the free end of said plunger, a flange integral with said collar, a plurality of pins fixed to one of said flanges and passing through apertures provided in the other of said flanges to guide the

movement of the collar as it slides on the plunger, means on said pins to limit the movement of the collar, said collar extending at least to the free end of said plunger when it is urged to the furthest limit of its possible movement, spring means between said flanges to urge the collar toward the grooved end of the plunger whereby a channel is formed by said groove between the plunger and the collar, said collar having an opening therein through which a strip may be fed into the channel, means to feed a strip into the channel whereby it is forced to take the shape of the channel, a pressing member reciprocable relatively toward said grooved plunger for engaging the strip in the channel, stripping means interposed between said plunger and said pressing member for relatively lifting the pressed ring from said plunger as the plunger is retracted, said stripping means driving said resiliently mounted means before it when the plunger and presser member are reciprocated toward each other, and means for reciprocating said plunger and pressing means toward and away from each other.
